CLAIM

The ornamental design for a locking head for a bundling strap, as shown and described.

DESCRIPTION

FIG. 1 is a top perspective view of the locking head showing my new design;

FIG. 2 is a bottom perspective view of the locking head of FIG. 1;

FIG. 3 is a first side elevational view, thereof;

FIG. 4 is a front elevational view thereof;

FIG. 5 is a second side elevational view thereof;

FIG. 6 is a rear elevational view thereof;

FIG. 7 is a top plan view thereof;

FIG. 8 is a bottom elevational view thereof; and,

FIG. 9 is a perspective view of the locking head shown engaged by a strap securing a bundle of wires, which are shown in broken lines for illustrative purposes only and form no part of the claimed design.
